UNITED STATES PATENT OFFICE.

GEORGE SIGEL LONNON AND FRANK MALLETT, OF SOUTH PUEBLO,
COLORADO.

BOLT-CUTTER.

SPECIFICATION forming part of Letters Patent No. 372,756, dated November 8, 1887.

Application filed April 16, 1887. Serial No. 235,117. (No model.)

To all whom it may concern:

Be it known that we, GEORGE SIGEL LONNON and FRANK MALLETT, citizens of the United States, residing at South Pueblo, in the county 5 of Pueblo and State of Colorado, have invented new and useful Improvements in Bolt-Cutters, of which the following is a specification.

Our invention relates to improvements in bolt-cutters; and it consists in a certain novel 10 construction and arrangement of parts for service, fully set forth hereinafter, and specifically pointed out in the claim.

In the accompanying drawings, Figure 1 is a side view of our cutter. Fig. 2 is a face or 15 front view thereof. Fig. 3 is a side view with the jaws open. Fig. 4 is a detail perspective view of the stop for the handles. Fig. 5 is a similar view of the upper ends of the handles, showing the cam ends thereon.

20 Referring to the drawings, in which similar letters denote corresponding parts in all the figures, A A designate the handles or reins of the cutter pivoted together at the upper ends by the bolt B, which also passes through eyes 25 in the lower ends of the arms C C' of the link C. The said reins are widened toward the upper ends and extended a short distance above the bolt B, and the said projecting portions are rounded to form cams D D', for a purpose 30 hereinafter explained.

E is a rigid or stationary jaw of the cutter, semicircular in form, with the cutting-edge or 35 knife E' having a straight or vertical face, as shown, and the said jaw is firmly secured to the upper end of the said link, between the arms thereof, by having a perforation in the upper side of said jaw passed over a short stud on the under side of the said upper end of the link.

40 F is the movable jaw, similar in shape to the upper or rigid jaw, pivotally secured at the rear end to the rear end of the said upper jaw and adapted to operate vertically between the lower ends of the arms of the link.

45 G is a flat leaf-spring bent into a curved form and placed between the said jaws, with the ends thereof pressing, respectively, against the under side of the upper jaw and the upper side of the lower jaw. This spring forces the 50 jaws E F apart, and the jaw F will move in the plane of the jaw E, so that when the edges

of the knives are forced together they will cut directly and effectively. It will be seen that the spring G is sufficiently strong to securely and firmly hold the upper jaw in place on the 55 stud, before mentioned, in the upper end of the link, even when the lower jaw is lowered to its farthest extent.

When the reins or handles are spread, as seen in Fig. 3, the jaws will be separated by 60 the action of the said spring, and as the said reins are drawn toward each other the cams on the upper ends thereof, operating against the lower surface of the movable jaw, will force it up and cause the edges of the knives 65 to bite together.

H represents an adjustable stop, comprising a body, I, having an opening therein to receive one of the reins, the thumb-screw I', to impinge at the inner end against the said handle and bind the said stop in the desired position, and the ear or projection I' on the side of the said body, adapted to serve as a limit to the motion of the handles and prevent the same from passing each other. The object of 75 the said stop is to prevent the edges of the knives from coming in contact with each other; and it will be understood that the closer the said stop is placed to the fulcrum or pivot of the handles the farther apart the lower ends 80 thereof will be held and the less will be the motion of the knives.

When it is desired to lay aside the tool, the stop is removed, the handles brought together, and the stop replaced, with the ear or projection on the under side of the handles, thus holding them together so that they occupy less space than when extended by the action of the spring.

It is not absolutely necessary to remove the 90 stop to lock the tool in the closed position, as there is sufficient lateral give or spring in the handles to allow the same to be sprung apart far enough to pass the said ear or projection, and thus lock the jaws and handles without 95 the inconvenience above mentioned.

K is a small stud on the side of the lower jaw, to prevent the same from being drawn accidentally out of the link, thus providing means to maintain the parts of the tool in their 100 proper relative position, as seen in the annexed drawings and herein described.

The operation of the implement will be readily understood from the foregoing description, and it will be seen that it is a simple, light, and strong device, well adapted in every way to satisfactorily accomplish the work for which it is designed. The link embracing the jaws, being placed at the front ends thereof, is adapted to serve as a powerful brace thereto, to prevent all straining of the tool. The action of the movable jaw is direct, guided laterally by the side arms of the link, and is prevented from being displaced by the stud on the side thereof. The leaf-spring is held securely in place laterally by the said side arms, and is prevented from slipping forward by the rear sides of the knives or cutters. The power exerted upon the lower side of the lower jaw by the two cams situated only a very short distance from the fulcrum, and actuated by the long handles or reins on the opposite side of the said fulcrum, is very great, the leverage being tremendous and calculated to raise the said movable jaw with force sufficient to sever any bolt which is possible to be received between the jaws; also, the device provided for limiting the motion of the jaws is extremely effective, and by simply removing the stop and

replacing it after passing the handles, or by springing the handles slightly apart, the said stop is caused to perform the function of a lock to the reins and jaws to prevent their spreading by the action of the spring.

Having thus described our invention, what we claim, and desire to secure by Letters Patent of the United States, is—

The combination, with the handles, of the stop H, placed on one of the handles and secured thereto by the thumb-screw I', and provided with the projection I², arranged in the path of the other handle, substantially as specified.

In testimony that we claim the foregoing as our own we have hereto affixed our signatures in presence of two witnesses.

GEORGE SIGEL LONNON.
FRANK MALLETT.

Witnesses to signature of George Sigel Lonnon:
